UNITED STATES PATENT OFFICE.

THEODORE S. BINDSCHEDLER, OF DETROIT, MICHIGAN.

TIMING SYSTEM.

964,743.

Specification of Letters Patent. Patented July 19, 1910.

Application filed November 15, 1908. Serial No. 593,031.

To all whom it may concern:

Be it known that I, THEODORE S. BINDSCHEDLER, a subject of the President of Switzerland, residing at Detroit, in the 5 county of Wayne and State of Michigan, have invented certain new and useful Improvements in Timing Systems; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in means for timing the hair springs on balance wheels of watches and 20 clocks. The manufacturers of watches and clocks usually perform this work or rather have it performed by highly skilled labor without the use of any special appliance, and after the hair springs and balance wheels are placed in the movements.

25 The object of the present invention is to provide means which will enable this class of work to be done by unskilled labor and much more expeditiously than heretofore, and in a most accurate manner.

30 In the operation of the timing system, the length of the hair spring is measured and a crimp is formed therein at the end or near the end to indicate the point at which the spring is to be pinned when placed in the 35 movement.

Preceding a detailed description of the invention, reference is made to the accompanying drawings, of which—

Figure 1, is a side elevation of the vibrator. Fig. 2, is a top plan view of the instrument or vibrator showing the same connected in an electric circuit with a master clock. Fig. 3, is a top plan view of one end of the lever of the vibrator showing the adjusting, 45 crimping, and cutting-off mechanism. Figs. 4 and 5, are details of finished hair springs.

In a detail description of the invention, similar reference characters indicate corresponding parts.

50 Referring to the vibrator, the elements constituting the same, are mounted upon a base 1 and comprise the following instrumentalities: a standard 2 which carries a pivot pin 3 engaging counter-sunk screws 4 and thus forming pivots for the forked end, 55 of a vibrating lever 6. The screws 4 pen-

trate the arms 5 or the forked or bifurcated end of the lever, and the friction between the lever and its fulcrum is equalized so that the position of the lever is always maintained in 60 a true central plane. Also mounted upon said base is a magnet consisting of two coils 7 which have cores 8 and are instrumental in magnetically attracting an armature 9 which crosses the lever 6 and is attached thereto. 65 The magnet is energized intermittently by the same being in contact with the battery A and a master clock; the pendulum B of which is only shown. The pendulum is pivoted at C and is provided with contacts D which 70 engage stationary contacts E. It will thus be seen that at each end of the swing of the pendulum, the circuit will be closed, the magnet energized, and the lever 6 will be drawn down. The downward movements of 75 said lever are limited by the impact of collar 12^a on the plunger 12 with a fiber washer 12^b. The upward movements of the lever 6 are arrested by a screw 10 which penetrates the upper end of a standard 11 and is engaged 80 by a projection 10^a on the upper side of the lever to stop the same which serves to cushion the contact between the screw and lever. The standard 11 is recessed on one side to provide space for the lever to pass through. 85 The upward vibrations or movements of the lever are accomplished by means of a spring 13 which is inclosed within the base of the standard and the upper end of which engages a plunger 12. The tension of the 90 spring 13 is controlled by an adjusting screw 14 which penetrates the lower end of the standard and upon which the spring rests.

Extending from the free end of the lever 6 is a die block 15 in which is mounted a short 95 shaft 16, on the lower end of which is mounted a small roller 17, and on the upper end of said shaft is a finger-piece 18 by which the shaft is rotated. A washer 19 and a spring 20 creates sufficient friction to prevent the shaft 16 from rotating freely.

Mounted in the same plane with the roller 17, is an idler roller 21 which is mounted on a rod 22 having bearings in lugs 23 projecting from the lever 6. A spring 24 normally 105 maintains the two rollers 17 and 21 together, but they may be separated to permit of the insertion of the end of a hair spring 24 by finger-pieces 25. The hair spring is guided to the rollers 17 and 21 by a slot 26 110 extending through the die block. The slot referred to, also guides the hair spring in

the front of a die 27 which is part of the die block 15, where the hair spring is crimped or marked as at 35, and is cut off. The crimp indicates the point where the end of the hair spring is pinned to the support which maintains it in operative position in the clock or watch movement. The die 27 works in connection with the die 28 on a plunger rod 29 which is mounted in apertured lugs 30 projecting from lever 6, and said plunger rod is controlled by a spring 31. The die 28 is operated by finger-pieces 32 to crimp and sever the hair spring and to prepare the same for attachment as shown in Fig. 4.

In Figs. 1, 2 and 3, I have shown the vibrator or instrument designed to adjust to time a hair spring of the form shown in Fig. 4 with the crimp 35 outward, but it will be understood that the instrument may be designed to adjust a hair spring with the convolutions running in the opposite direction and with the crimp lying inwardly as shown in Fig. 5.

Referring to Fig. 1, in placing a hair spring and balance wheel in a position to be timed, the short end of the shaft 37 of the balance wheel 38 is placed in the countersunk end of a supporting screw 39 which penetrates the base and is adjustable. The upper end of the staff 37 extends into the spring 34 but is loose. The upper end of the spring is inserted between the two rollers 37 and 21. The vibrator is then permitted to operate. The vibrations of the lever impart reciprocating movement to the spring and balance wheel, and these reciprocating movements, if not properly responsive to the movements of the lever, the two elements may be brought in synchronism by means of the shaft 16 and rollers 17 and 21. After the spring is thus brought into synchronism with the lever 6, which it will be understood, is in synchronism with the master clock, the spring is crimped and cut off and the rollers are separated and the spring permitted to drop from the instrument and another spring to be inserted.

I claim:

1. In an electrical apparatus for timing clocks, the combination with an electric circuit including a master clock and an electro-magnet, of a timing device in operative re-

lation with said magnet, said timing device comprising a vibrator actuated in unison with the master clock, means for holding a hair spring in the vibrator so that the vibrations of said hair spring will be in unison with the vibrator and the master clock, and means for marking the hair spring at the point where it is to be pinned to the movement.

2. A vibrator for timing the hair springs of clocks and watches, comprising a lever, electrical means for vibrating said lever in unison with a master clock, means for supporting a hair spring and balance wheel below the lever, means supported on the lever for holding and determining the lengths of the springs, and means for marking or timing said springs to indicate the point of pinning said springs to the clock or watch movements.

3. In a device for timing the hair springs of clocks and watches, the combination of an electric circuit, a master clock and an electro-magnet in said circuit, a lever vibrated by said magnet, a chuck supported on said lever having a slot for the insertion of the outer end of the spring, rollers carried in said chuck and engaging the end of the spring projected through said slot, and a die carried on said lever for marking the spring at the point where it is to be pinned in the movement.

4. In a device for timing hair springs of clocks and watches before they are placed in the movements, the combination with an electric circuit, a master clock and an electro-magnet in said circuit, a lever vibrated by said magnet in unison with the master clock, the fulcrum end of said lever terminating in forks, each receiving an independent pivot, whereby the friction due to the fulcrum of said lever is equalized, a chuck supported on said lever and having a slot for the insertion of the spring, rollers in said chuck, one of said rollers being independently movable to determine the length of the spring.

In testimony whereof I affix my signature, in presence of two witnesses.

THEODORE S. BINDSCHEDLER.
